(57) **CLAIM**

The ornamental design for a lever compression latch, as shown and described.

DESCRIPTION

FIG. 1 is a front isometric view of a lever compression latch, showing our new design;

FIG. 2 is a rear isometric view of thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top elevation view thereof; and,

FIG. 8 is a bottom elevation view thereof.

In the drawings, the broken lines indicate environmental structure that forms no part of the claimed design. The dash-dot lines indicate the boundaries of the claimed subject matter.
